UNITED STATES PATENT OFFICE.

JOHN C. GREENWAY, OF ISHPEMING, MICHIGAN.

CAR-UNLOADING APPARATUS.

SPECIFICATION forming part of Letters Patent No. 752,449, dated February 16, 1904.

Application filed January 14, 1903. Serial No. 138,993. (No model.)

To all whom it may concern:

Be it known that I, JOHN C. GREENWAY, of Ishpeming, Marquette county, Michigan, have invented a new and useful Car-Unloading Apparatus, of which the following is a full, clear, and exact description, reference being had to the accompanying drawings, forming part of this specification, in which—

Figure 1 is a general front elevation of my improved apparatus in position over a car. Fig. 2 is a top plan view of the same. Fig. 3 is a top plan view of the trolley I employ. Fig. 4 is a general side elevation of the trolley. Fig. 5 is a sectional side elevation of the supporting and actuating mechanism for the movable head of the device. Figs. 6 and 7 are cross-sections on the lines VI VI and VII VII, respectively, of Fig. 5. Fig. 8 is a side elevation of the mechanism for raising and lowering the squared shaft. Fig. 9 is an end elevation of the apparatus. Fig. 10, Sheet 1, is a detail view showing the arrangement of the track and wheels for the trolley, and Fig. 11 is a side elevation showing my preferred form of head.

My invention relates to the discharging of lump or granular material from dumping-cars, and is designed to assist in this operation by providing mechanism for loosening the material, which often arches over the openings and requires the use of hand labor. It is also designed to thaw out frozen material in such cars and mechanically loosen the material at the same time.

In the drawings I show a traveling bridge having end supports 2 2 of general A shape, which carry upper parallel tracks 3 3, preferably formed of rolled channels with their flanges 4 projecting inwardly toward each other, as shown. The trolley, which carries the actuating parts of the loosening apparatus, is mounted upon wheels 5, which move within the flanges of the channel, as shown in Fig. 10, thus preventing any lifting of the trolley during the downward movements of the loosening-head. The bridge itself is mounted upon wheels 6 and 6', which travel upon rails 7 7, the bridge preferably being of sufficient length to straddle two or more railway-tracks 8 8, upon which the dumping-cars 9 are moved.

To move the bridge along its track, I preferably provide an electric motor 10, having spur-gearing connection 11 with a main driving-shaft 12 through a combined friction-clutch and brake 13. The shaft 12 is connected at each end by bevel-gearing 14 with vertical shafts 15, connected through bevel-gearing 16 at their lower ends with the shafts to which the wheels 6' at one side of the bridge are secured.

Upon the trolley-frame 17 are-mounted two ring-shaped bearings 18 18, within which fit the circular end hubs 19 of a gimbal-frame 20. The central part of this gimbal-frame is provided with circular bearings 21, which receive the trunnions 22 of the vertically-extending guide-frame 23, containing a vertically-movable hollow squared shaft 24. The squared shaft is provided at one side with a series of rack-teeth 25, which are engaged by a pinion 26 upon a shaft 27, supported in brackets 28, secured to the sides of the vertical guide. The shaft 27 has at one end a clutch connection 29 with worm-gear 30, connecting to shaft 31, carrying toothed wheel 32, intermeshing with pinion 33, driven by electric motor 34. This motor is supported upon suitable brackets 35, secured to the vertical guide 23, and is provided with a brake device 36. The worm-gear connection provides for a slow up-and-down movement of the head during its rotation, and to give a more rapid vertical motion to this head when desired I connect the shaft 27 at its opposite end through bevel-gear 37 with a shaft 38, having clutch connection with a toothed wheel 39, also engaging the pinion 33. By throwing either one of these clutches the head may be given a quick reciprocating movement or a slow up-and-down movement. This digging and loosening head, one form of which I have shown at 40 in Fig. 1, is secured to a hollow cylindrical shaft 41, which extends upwardly through the hollow squared shaft 24 and above the vertical guide is splined to a pinion 42, intermeshing with toothed wheel 43 upon the shaft of an electric motor 44, mounted upon the guide and having a brake-wheel 45. The rotary connection with the tubular shaft 41 allows the shaft 41 to be rotated in any and all

positions, while the vertical movement of the squared shaft will impart a similar movement to the shaft 41 through the extension 24' on the squared shaft engaging the collar 41' on the shaft 41. If frozen material is being acted upon, steam or other heated fluid may be supplied through a rotary connection at the upper end of the shaft 41, this heated fluid emerging through the holes 52 at or near the head, as shown in Fig. 11, and thawing out the frozen material, while the head acts to loosen it.

In using the apparatus the bridge is moved to the desired point over the cars or the dump-cars are moved thereunder, and the trolley is moved along the bridge to the desired point over the car. The drop-doors of the car being opened, the gimbal-bearings are adjusted to bring the driving-shaft of the head to the desired angle, the right-angle axes giving a universal adjustment. When adjusted to the desired angle, the screws 46 are actuated to clamp the gimbal. The head may then be reciprocated either slowly or rapidly to punch down through and up through the material, and at the same time may be rotated to drill its way down or up or in both directions. It is evident that either or both motions may be used at any point desired, and the shaft may be adjusted from time to time and the trolley moved along the bridge, the bridge being moved to bring the tool throughout all points of the car. The material is thus loosened and at the same time the frozen material may be loosened by the introduction of heated fluid.

Instead of the plain drill-head shown in Fig. 1, for convenience, I prefer to use an expanding-head of barbed type, one form of which is shown in Fig. 11. In this form the end 47 of the head is provided with a tubular extension 48, having pivoted thereto oppositely-extending links 49, connected to inwardly-extending links 50, having loose slotted connection with guides 51. In forcing the head down through the material the links will assume the position shown in dotted lines, while in lifting the head the resistance will cause the link to open into the position shown in full lines, thus increasing the size of the hole, and consequently the loosening effect.

The advantages of my invention will be apparent to those skilled in the art. The use of hand-labor, a large amount of which has heretofore been necessary in loosening the material and causing it to slide down through the bottom openings of the car, is done away with and the action obtained mechanically. The use of motor mechanism is highly efficient in causing the rapid discharge of the car contents, thus effecting a large saving in time and labor.

The device may be used for loosening the material in either cars, bins, buckets, or other receptacles having openings at or near the

bottom for discharging it. The mechanism for actuating the head or loosening device may be varied, as well as the supporting mechanism, the motors employed, &c., without departing from my invention.

I claim—

1. An unloading device comprising a bridge, a trolley movable thereon, a loosening-head mounted on the trolley and mechanism for moving the head vertically to loosen the material in the receptacle beneath; substantially as described. 75

2. An unloading device comprising a depending loosening-tool, mechanism for rotating the loosening-tool, and mechanism for positively moving it vertically upwardly and downwardly; substantially as described. 80

3. An unloading device comprising a trolley, a vertically-movable loosening-tool depending therefrom, mechanism on the trolley for positively moving the tool vertically upwardly and downwardly, and mechanism for rotating the tool; substantially as described. 85

4. An unloading device comprising a hollow depending stem provided with a head and having perforations at or near its lower end, a connection leading from the stem to a source of fluid, and mechanism for moving the stem; substantially as described. 90

5. An unloading device comprising a depending hollow stem having a lower head and provided with perforations, a connection leading from the stem to a source of heated fluid, and mechanism for moving the stem in a vertical direction; substantially as described. 95

6. An unloading apparatus comprising a traveling bridge, a trolley movable along the bridge, and carrying a depending loosening-tool, and mechanism on the trolley for actuating the tool to punch or loosen the material in the receptacle beneath; substantially as described. 105

7. An unloading device comprising a depending stem having a head, mechanism for adjusting the stem-support to different angles, and mechanism for giving the stem a positive upward or downward movement at any adjusted angle; substantially as described. 110

8. An unloading device comprising a traveling bridge and trolley movable thereon supporting a depending stem having a loosening-head affixed to its lower end; mechanism for adjusting the stem to different angles; and mechanism for positively actuating the stem at any adjusted angle to loosen the material beneath, substantially as described. 115

9. An unloading device comprising a depending loosening-rod, extending through a support, mechanism for adjusting the support in any direction, and mechanism for rotating the rod and moving the same in a vertical direction; substantially as described. 125

10. A support mounted on a universal-joint device, mechanism for clamping the support at the desired angle, a loosening-bar extend- 130

ing downwardly from the support, and mechanism for positively actuating the bar to loosen the material beneath it; substantially as described.

5 11. In unloading apparatus, a traveling bridge, a trolley mounted thereon, mechanism for preventing lifting of the trolley from its track, a punching-bar mounted on the trolley and depending therefrom, and mechanism for reciprocating said bar; substantially as described.

12. In unloading apparatus, a traveling bridge arranged to straddle a car-track and car, a trolley movable along the bridge and having a depending punching-bar, and mechanism for actuating said bar to loosen the material in the car; substantially as described.

13. A traveling bridge, a trolley movable thereon, a depending loosening-bar carried on

the trolley and mechanism on the trolley for 20 rotating and moving the bar vertically to loosen the material beneath; substantially as described.

14. An unloading device comprising a depending loosening-stem, mechanism for moving the same vertically into the material, and a head arranged to expand automatically when lifted; substantially as described.

15. A trolley having a depending loosening-stem, mechanism for moving the stem vertically into the material, and an expanding-head carried on the stem; substantially as described.

In testimony whereof I have hereunto set my hand.

JNO. C. GREENWAY.
